UNITED STATES PATENT OFFICE

2,605,513

FLOORING

Gustaf Kähr, Stockholm, Sweden

Application October 3, 1946, Serial No. 700,917
In Sweden October 18, 1945

4 Claims. (Cl. 20—6)

1

Flooring made up of boards is usually laid on joists which are set on a false ceiling and located in parallel relation to one another, to which the boards are nailed, whereby the space between the joists may be filled with a granular or fragmentary material such as crushed coke. The last-mentioned material does not provide a supporting surface for the floor however, which is therefore supported and carried exclusively by the joists. On this account the distance between the joists, or the resistance of the boards to bending, or their thickness, must be so selected that the boards are not subjected to any downward deflection by the load on the floor. For this reason relatively thick boards are usually employed and the distance between the joists must likewise be kept relatively short. The total quantity of timber in the flooring and joists will therefore be comparatively large. Furthermore, the employment of joists laid directly on the false ceiling is accompanied by the disadvantage that the sound insulation of the false ceiling will be relatively poor since sound, and particularly the sound of impacts, is easily transmitted through the joists.

The present invention has for its object to provide a cheap form of flooring which economises in timber and which possesses very good sound-insulating properties, and is characterized mainly by that the flooring is laid on sand or a similar material, as a supporting foundation. As the flooring according to the invention thus rests with the whole of its underside on a compact sand support the pressure due to the load on the floor will be distributed relatively uniformly over a large area and consequently the floor boards will not be subjected to deflection. The boards may therefore be made relatively thin whereby a considerable saving in timber is effected. On the other hand it is important that the flooring should lie as closely as possible against the sand foundation in an unloaded condition also, so that no intermediate space is formed which might give rise to movements of the flooring when it is loaded temporarily. For this purpose, according to the invention, the flooring is preferably made of laminated boards which consist, in a known manner, of two or more layers of wood glued together, each of which may itself be made of strips or veneers. Boards of this kind possess the property of retaining their flat form and furthermore, if they are made sufficiently thin they may have the property of holding by their own weight against the foundation over practically their whole surface so that they lie closely

2

against the foundation similarly to a carpet. The requisite flexibility of the flooring or floor boards for this purpose may be further increased by providing the strips composing the lower strip layer of the boards with a transverse cut across the fibres, or by forming the strip layer of relatively short strips. Boards of this kind will, however, be sufficiently strong and stiff to permit them to take up local pressure stresses without bending and without deformation of the sand layer inasmuch as the pressure of the load on the sand foundation is distributed by the boards over a larger area than the remainder of the floor surface on which the pressure is acting. 10 To ensure the distribution of the pressure in this manner and at the same time obtain close jointing of the boards the latter are preferably provided with tongues and grooves along their longitudinal edges. 15 For the purpose of holding the boards together in a transverse direction use may be made of joists as for ordinary floors, on which the boards are laid and nailed, whereby the thickness of the joists and/or the thickness of the sand layer must be so adjusted however, that the joists do not lie directly on the fixed false ceiling but rest on the sand foundation similarly to the boards. Owing to the fact that the floor is supported over its whole surface by the sand foundation, these joists need not be laid so close to 20 one another as in the case of ordinary floors but can be arranged at a considerably greater mutual distance apart whereby the number of joists is reduced. For floors composed of laminated boards relatively wide boards may be employed with advantage inasmuch as a number of narrower boards may be combined with one another already during their manufacture, to form wider boards or slats. For this purpose it is not necessary to use long bars for the joists, and 25 the latter may take the form of relatively short bars, plates or blocks which are located transversely across the joints between adjacent boards or slats and to which the boards or slats are nailed or fixed by other means. 30 In consequence of the fact that the floor is separated from the fixed false ceiling by a layer of sand or the like, effective sound insulation is obtained. In fact, a layer of sand possesses very 35 good sound-insulating properties, particularly with regard to the sound of impacts. As the joists are also separated from the false ceiling by a layer of sand no transmission of sound can 40 take place through the nails driven into the joists as is the case with ordinary flooring laid 45 on joists. 50

The invention will now be more particularly described with reference to the accompanying drawings which show different forms of construction for floors arranged according to the invention. Fig. 1 is a plan view and Fig. 2 a cross-section of one form of construction of the floor. Fig. 3 is a cross-section to an enlarged scale of a laminated board. Figs. 4 and 5 show in plan view and cross-section another form of construction for the floor. Figs. 6 and 7 and 8 and 9 respectively show in plan view and cross-section different forms of construction for sound-insulating joists and supporting plates.

In the floor shown in Figs. 1 and 2 the flooring is composed of laminated boards, which are laid on a supporting foundation 2 of sand or similar granular material. The boards which are tongued are held together in a transverse direction by joists 3, two of which are arranged along two opposite sides of the floor surface whilst the remainder are arranged parallel with these at the same mutual distance apart. After the layer of sand 2 has been placed in position and smoothed over so that it has a level upper surface, the joists 3 are placed on the sand foundation whereupon the board are laid consecutively across the joists and nailed to the latter. The joists may consist of relatively thin ribs. In no case should they have a greater thickness than to allow a sufficiently thick layer of sand to lie between the joists and the fixed false ceiling 4 which usually consists of concrete. In some cases the joists may have a trapezoid-shaped cross-section and may be placed with the wider of the two parallel sides lying against the underside of the boards.

Fig. 3 shows in section an example of a laminated board which may be used with advantage in a floor according to the invention. The board consists of an upper wearing surface 5 of parquet strips which may be arranged in any approved pattern but may also be so arranged that all the strips lie side by side in the transverse direction of the board, and an under-layer consisting of longitudinal strips 6 to which the wearing surface is glued. The boards are provided with tongues 7 and grooves 8 formed in the strips 6 along the longitudinal sides of the board. To still further reduce any possible tendency to warping in the boards, the strips 6 may have longitudinal cuts 9 sawn in them on opposite sides. Such cuts may in some cases also be formed in the transverse direction of the strips. Owing to the fact that the whole surface of the floor rests on a compact sand foundation the boards may be made very much thinner than is possible when laying the boards on supporting joists in the known manner. To prevent the sand from penetrating into the cuts 9 the board may be provided on the underside with a covering of veneer or paper which covers the whole of the underside of the board.

In the form of construction illustrated in Figs. 4 and 5 relatively wide boards or slats are employed. In the example shown each slat 10 is composed of a number of narrower boards 11 which are joined to one another by tongues and grooves and are glued together in the grooves. To prevent the slats from being broken or injured during transport cross-bars 12, 13 may suitably be mounted on the underside, which are fastened by nailing or gluing so that the slat receives adequate stiffening in a transverse direction. The cross-bars may either be arranged obliquely or in a direction at right-angles to the edges of the board, as shown in Fig. 4.

In order to facilitate the joining of the boards or slats, use may be made of screw jacks by means of which the boards can be pressed together at the sides, and which are thereby supported against one or the other of the two opposite walls.

In the form of construction according to Figs. 4 and 5 the joists may advantageously be replaced by wood plates or blocks 14 which are placed in suitable numbers along the joints between the slats as shown in Fig. 4. The plates 14 serve in a similar manner to the joists 3 in Figs. 1 and 2 to hold adjacent slats together, for which purpose the slats are nailed to the plates or attached to them in some other manner. The plates 14 may be fixed to the slats while the latter are being manufactured. When laying the floor each new slat is joined to the preceding one by tongues. On the other hand it is not necessary to fix the new slats to the plates 14 projecting at the edges of the preceding slat. The said plates merely serve to partially relieve the tongued joints from the stresses at the joints.

The plates 14 may also be employed for holding adjacent boards together when the flooring is composed of single boards according to Figs. 1-3. They may also consist of iron plates provided with fixed pins which penetrate into the boards and hold them when they are laid over the plates and pressed against the latter by hammer blows.

In some cases it may be found suitable to use the joints as supporting members also, for which purpose they are placed in a known manner on the fixed false ceiling and the joists, together with the layer of sand laid between them, form the supporting foundation for the floor. In order to obtain good sound insulation, according to the invention, the joists are thereby composed of two or more layers laid over one another, at least one layer of which consists of a material possessing sound-insulating properties, such as pressed wood fibre mass of the same kind as in the known wood fibre plates, whilst the remaining layers may be of wood. Figs. 6 and 7 illustrate a joist constructed in this manner. It consists of a lower, relatively wide strip or board 15 which is placed directly on the concrete foundation 4, with a narrower rib or strip 16 of wood fibre material placed above it and an upper bar 17 of wood, to which the boards are nailed. The various layers are suitably joined to one another by glueing. For the sound-insulating intermediate layer 16 a highly porous wood fibre material may be employed with advantage. The latter may in some cases be replaced by felt or a similar compressed material, which possesses the advantage that by suitably adjusting the quantity of sand between the joists it is possible to ensure that the whole surface of the floor located between the joists will lie on the sand foundation in such a manner that the pressure load on the floor is taken up partly by the sand layer and partly by the joists. In some cases the arrangements may be such that the pressure load is only taken up to a slight extent by the joists, the greater part being supported by the sand layer.

When plates or blocks are employed in place of joists, as shown in Figs. 4 and 5, these plates or blocks may also be placed directly on the fixed false ceiling. They may be put together in a similar manner to the joists in Figs. 6 and 7. Figs. 8 and 9 show a form of construction for a plate assembled in this manner. The plates may be fixed in a suitable way in relation to the foundation, for example, by means of holders of iron strip or the like cast into the concrete support.

As a filling compound for the false ceiling dry sand of ordinary composition may be used, such as quarts sand or sand of other kinds, or generally speaking, a granular mineral material which does not exhibit adhesion in a dry condition, or so little adhesion between the grains that the mass is easily deformed or levelled out under the action of pressure.

What I claim is:

1. Sound absorbing flooring consisting of a cementitious foundation, a horizontally confined layer of sand on said foundation and interlocked floor boards floatingly and exclusively supported in their whole extension and with their total weight by the sand layer, said boards being laminated and flexible and forming a flooring and lying by their own weight in direct contact with the surface of the sand layer and the said sand layer being substantially of a uniform thickness over the whole floor surface.

2. Sound absorbing flooring consisting of a cementitious foundation, a horizontally confined layer of sand covering the whole of said foundation and being of a substantially uniformly thin thickness, wood ribs embedded in the sand layer and having their upper surfaces in level with the upper surface of the sand layer, and flexible, laminated tongue and groove matched wood boards nailed to the ribs and forming together with the ribs an upper flooring lying in direct contact with and supported in its whole extension exclusively by the sand layer.

3. A sound absorbing flooring as claimed in claim 2 in which the boards consist of an upper wearing layer of parquette strips and an under

5

layer glued to the upper layer and consisting of longitudinal strips.

4. A method of laying a flooring on a lower foundation consisting in covering the whole foundation with a layer of sand of a uniform thickness, placing ribs of wood loosely on the sand layer in parallel rows extending along the whole flooring surface, levelling the upper surface of the sand layer and allowing same to dry, placing laminated boards on said ribs transversely thereof and nailing the boards to the ribs so as to form an upper flooring supported in its entire extension exclusively by the sand layer.
